UNITED STATES PATENT OFFICE.

THEODORE WADLEIGH, OF SOMERS, IOWA.

CONICOVATE GRINDER BURR.

Application filed June 7, 1926. Serial No. 114,168.

My invention relates to that type of burrs for grinding mills, particularly for grinding feed such as ear corn, which are of generally conical form and are arranged in either up-right or horizontal position in the mill, and I have modified this conical form for certain purposes which will be made clear, and produced a form of burr which I have termed "conicovate".

This type of mill includes an outer stationary burr and an inner rotating burr, and one of these members, generally the inner burr, is adjustable longitudinally in order to adjust the fineness of reduction or to compensate for wear. The difficulty heretofore has been that in adjusting the burrs for finer grinding or reduction, the outlet portions of the burrs approach each other too rapidly, as compared with the approach of the crushing portions of the burrs, and the result is that there is a clogging of the substance at the outlet, which of course results in loss of time, unsatisfactory reduction, and undue wear on the burrs which greatly shortens the life thereof. It is this difficulty that I have sought to overcome by modifying the shape of the burrs near the reduction or outlet end, and this is the object of the present invention.

My invention consists in the construction, arrangement and combination of elements hereinafter set forth, pointed out in the claim and illustrated by the accompanying drawing, in which—

Figure 1 is a longitudinal section of a portion of a grinding mill equipped with and illustrating my improved form of burrs and showing them in an adjusted position for relatively fine reduction.

Figure 2 is a similar view showing the burrs adjusted for extremely coarse reduction.

Figure 3 is a perspective view of the inner burr removed from the mill.

In the construction of the devices as shown the numeral 10 designates generally the frame of a mill which may be of any suitable form and construction and having a feed hopper 11 by which the substance to be ground is introduced. Suitably mounted in the frame 10, as by bolts 12, is an outer or stationary burr 13 of generally conical form, or rather frusto-conical, of hollow form and provided on its inner surface with any suitable form of teeth or crushing, grinding and reducing devices. Arranged

axially of the outer burr 13 and suitably journaled in the frame is a shaft 14 adapted to be rotated by any suitable power. In the present form of the device, in which the burrs are arranged in horizontal position, the shaft 14 is provided with inclined lugs 15 in the throat of the hopper to carry the substance to be ground toward the burrs as the shaft is rotated; but in the vertical type of mill dependence may be placed upon gravity to cause the substance to so travel. Mounted on the shaft 14, within and in a position to cooperate with the outer burr 13, is an inner burr 16, also of hollow construction. Within the inner burr 16 is a core 17 which is flanged at its base, and partially embracing the apex of said inner burr is a cap 18, which core and cap are secured to the shaft 14 as by bolts 19 and 20 respectively. The cap 18 holds the apical portion of the burr 16 to the shaft, and the base portion thereof is held by means of bolts 21 passing therethrough and through the flange of the core 17. The adjustment of the inner burr relative to the outer burr is accomplished by shifting the shaft 14 longitudinally by any suitable and common means, not shown.

In this type of grinding mills the taper of the inner burr is more pronounced than that of the outer so that there is a greater annular space between their apical portions, where the substance to be reduced enters the burrs and is crushed or broken, than between their base portions, where the substance is ground and reduced to meal or varying degrees of fineness. In the usual construction the taper or slant is uniform from end to end of each burr, or in other words the inner surface of the outer burr and the outer surface of the inner burr are, throughout, true conical elements. My improvement consists in modifying this construction at the base portions of the burrs by forming such base portions on segments of spheres which merge into the conical elements and continue to the base end of the burrs. With respect to the outer burr, the spherical portion begins substantially at the point *a* and with respect to the inner burr it begins substantially at the point *b*, in both instances continuing to the larger end of the burr, which would be substantially on a diameter of the sphere. It is to be understood that the grinding surfaces of the burrs 13 and 16 are of any suitable type as indi-

cated conventionally in Figure 3, but the indication of these grinding surfaces has been omitted in Figures 1 and 2 in order to show more clearly the true shape of the burrs themselves.

It will be understood with respect to the usual type of burr, in which the grinding surfaces are formed throughout on conical lines of different tapers, that as the inner burr is adjusted for finer reduction, for instance from the position of Figure 2 to that of Figure 1, the base portions, where the fine grinding occurs, will approach each other more rapidly than will the apical portions, where the coarser reduction or crushing occurs, because of the convergence of the surfaces toward the base ends. The result is that the effective grinding surface near the base end is greatly reduced as such adjustment is made, and further that by the surfaces approaching each other at angles the tendency of the mill to clog is greatly increased. The fact is that in this type of mill, having the usual form of burrs, great difficulty has been found in operating the mill at all when adjusted for fine reduction, because of the constant clogging at the outlet; and further that excessive wear occurs on the relatively small area of the reducing surfaces which is actually used during such adjustment, thus greatly reducing the effective life of the burrs.

By reason of my peculiar formation of the base or reducing end portions of the burrs, namely on spherical lines rather than conical, when adjustment is made for instance from the position of Figure 2 to that of Figure 1, such base portions do not approach each other as rapidly as they otherwise would, and in fact do not approach as rapidly as do the conical portions toward the mouth of the mill. This is because in making such adjustment the spherical surfaces travel toward a position of substantial concentricity or to a position where they are substantially parallel, instead of converging

as in the ordinary form. It follows that such adjustment may be made, and finer reduction secured at the crushing end portion of the burrs, without restricting the grinding surface at the outlet end, or restricting the outlet itself, so that the objectionable tendencies above referred to are overcome. This materially increases the efficiency of the mill, particularly when adjusted for fine reduction, and lengthens the life of the burrs.

My improved burrs can be provided with grinding surfaces on their entire faces, and can be adjusted to grind to any desired reduction without clogging, even when the substance to be ground is wet. The burrs may be made each integral or in sections as here shown, and can be provided with any desired or suitable grinding surfaces. They are peculiarly adapted to grinding all kinds of stock feed and will grind faster and run more easily, because the burrs may be made of less diameter than the usual burrs, and thus being closer to the shaft require less power. They can of course be made in any desired size and either vertical or horizontal. Owing to the greater surface provided for fine reduction or finishing of the product being ground, the grinding surfaces of the burrs can be run farther apart which will save wear on the burrs and will require less power to run the mill.

I claim as my invention—

In a grinding mill, an outer burr and an inner burr cooperating therewith, one of said burrs being rotatable and longitudinally adjustable, said burrs having their apical portions of substantially conical formation and without curvature longitudinally and converging toward their delivery ends and having their base portions formed substantially as spherical segments, whereby when adjustment is made for finer reduction the conical surfaces will approach each other more rapidly than the spherical surfaces.

THEODORE WADLEIGH.
